UNITED STATES PATENT OFFICE.

ISAAC H. LEVIN, OF NEW YORK, N. Y.

ELECTROLYTIC CELL.

Application filed June 12, 1920, Serial No. 388,430. Renewed October 26, 1923.

To all whom it may concern:

Be it known that I, ISAAC H. LEVIN, a citizen of the United States, residing at the borough of Manhattan, city, county, and State of New York, have invented certain new and useful Improvements in Electrolytic Cells, of which the following is a specification, reference being had therein to the accompanying drawings, which form a part thereof.

My invention relates to electrolytic cells, and more particularly to a feed water system for such cells of the unipolar type by means of which the water in the electrolyte which has been decomposed will be replaced by a fresh supply of distilled water in accordance with the need of the cell.

Heretofore in electrolytic cells of the unipolar type used for generating oxygen and hydrogen, it has been the common practice to supply each cell with a fill cup having one or more pipes extending therefrom and terminating adjacent the normal level of the electrolyte in the cell. When such fill cups are used, it is necessary for the operator of a battery to inspect the cups from time to time, and refill them with distilled water as the supply of water stored therein becomes exhausted. These cups in addition to their function of renewing the supply of distilled water in the electrolyte, also serve as safety devices to permit a blowout of gases in the event that the level of the electrolyte adjacent the discharge end of the pipe leading from the cup to within the cell, reaches a subnormal level either through a failure to properly deliver distilled water into the cell, or through the development of excessive pressures upon one side, or the other, of the diaphragm from any reason whatsoever.

In a cell made in accordance with my invention, I provide means in conjunction with an electrolytic couple of the unipolar type wherein a cell, or each of the cells of a battery, will have distilled water delivered thereto from a storage tank containing same, whenever such is required, as determined by the working conditions within a cell.

Unipolar cells, particularly those of the type wherein the tank for the electrolyte is formed by the cathode of the cell, have a cover forming the gas chambers, a hydraulic joint open to atmosphere being formed about the top of the tank and a pendent flange upon the cover. The liquid forming the seal of said joint sometimes is connected with

the space within the tank so that the conditions of this seal will vary according to different pressure conditions within the tank; and permit a blowout through this seal in the event of the development of excessive pressures in the tank, this blowout feature being supplemental to that afforded by the fill cup.

In such a hydraulic joint, the level of the water will under normal conditions be considerably higher than within the cell, due to the relatively greater area of the body of electrolyte in the cell and the relatively higher or superatmospheric pressure acting upon said larger area. Hence during the operation of a cell, the water in the outer trough of the hydraulic joint is subject to much greater variation than is the level of the electrolyte within the tank, and in the event of a cell being shut down, the level of the electrolyte within the tank will rise while that in the outer trough of the hydraulic joint will be lowered to a disproportionately greater extent than the rise of the level of the water within the tank. Hence while the hydraulic joint at the top of the tank may be used as a medium for filling the cell, the level of the water in this joint does not truly represent the conditions within the cell, and it is therefore more desirable to renew the supply of distilled water by delivering it directly into the body of electrolyte within the tank.

In a cell made in accordance with my invention, I provide a distributing pipe leading from a reservoir containing distilled water and having a discharge pipe opening into the cell slightly below the normal level of the electrolyte therein. Said discharge pipe has in its length a valve mechanism controlled by a float acted upon by the electrolyte in the cell, so that water will be delivered to the cell only when a drop of the level of the electrolyte is such as to permit a fall of the float sufficient to actuate said valve. Immediately upon sufficient water having entered the cell to restore the normal level, the valve is closed by the rise of the float.

By controlling the flow of distilled water to the cell in this manner, I not only secure the automatic renewing of the supply of distilled water within the electrolyte, but the shutting down of the cell will, with the rise of the electrolyte in the cell, which always follows such closing down of the cell,

prevent any distilled water flowing into the cell from the reservoir, while the cell is not in operation.

Furthermore by arranging the float within the tank, the control of the valve will not be influenced to any appreciable extent by varying pressure conditions within the cell, since there will be no substantial variation in the level of the electrolyte upon either side of the diaphragm within the cell, since although there may be a material flow of electrolyte from one side of the diaphragm to the other with a fluctuation of pressure upon opposite sides of the diaphragm, the volume of water so flowing will not be sufficiently great as compared with the entire mass of water in the cell, to materially effect the level of the electrolyte sustaining the float.

Hence the actuation of the valve by the rise and fall of the float will depend solely upon the consumption of the electrolyte as a result of the decomposition thereof and the formation of the two gases, so that the renewal of the supply of water will be proportionate to the rate of decomposition of electrolyte.

To permit the use of the filling device as a vent in the event of a blowout, I preferably provide a break in the length of the discharge pipe to each cell, and surround this break with a cup. Although the feed system may be used with or without this cup feature, I prefer to use the cup, as it will ensure the feed of distilled water to the tank and maintain substantial uniform hydrostatic pressure conditions effecting the feed, at all times.

The invention consists primarily in an electrolytic cell embodying therein a pipe leading from a source of distilled water supply and discharging within a cell below the normal level of the electrolyte therein, a valve arranged in said pipe, and actuating means for said valve comprising means responsive to variations of the level of the electrolyte in the cell, and operative connections between said means and said valve, whereby said valve will be opened when the electrolyte in the cell reaches a subnormal level and will be closed when the electrolyte in the cell is at the normal level; and in such other novel features of construction and combination of parts as are hereinafter set forth and described, and more particularly pointed out in the claims hereto appended.

Referring to the drawings.

Fig. 1 is a longitudinal, vertical section through the upper part of a cell made in accordance with my invention; and

Fig. 2 is a transverse section of adjoining cells of a battery embodying the invention. Like letters refer to like parts in both of said views.

In the accompanying drawings, I have

shown the invention as applied to a cell of the unipolar type embodying a tank *a* forming the cathode or negative electrode, the top of which tank is closed by a suitable cover *b* forming gas chambers adjacent the top of the cell and co-operating with the upper portion of the tank *a* in a manner to permit the free circulation of the electrolyte adjacent the upper part of the cell, from one side of the diaphragm to adjacent the other side thereof. The detailed construction of this water circulation and the hydraulic joints is not essential to my present invention, which relates more particularly to the manner of automatically feeding distilled water into the cell to replace that decomposed during the operation of the cell.

The upper part of the tank *a* has a trough about the edge thereof formed by the walls *a'* and *a''*, while the cover *b* is provided with flanges *b'* and *b''* adapted to straddle the wall *a''*, the flange *b''* carrying a plate *b''* forming a trough within said flange *b''*. The flange *b'* has at one point thereof an opening *c* therethrough, and the trough formed by the plate *b''* communicates with the outer trough adjacent the wall *a'* through a horizontally extending tube *d* passing through an opening in the wall *a''* sufficiently large to permit the flow of the electrolyte into the trough formed between the wall *a''* and the flange *b'* from within the cell. In this manner gas-tight chambers are formed within the cell adjacent the cover *b*, and the electrolyte is permitted to flow through the various troughs in either direction, the trough adjacent the wall *a'* affording a vent to atmosphere in the event of the development of excessive pressures in the cell.

The diaphragm between the inner and the outer electrode is indicated at *e*, the inner electrode being indicated at *e'*. The terminal bars for the electrode *e* are shown at *e''*. Extending from a reservoir *f* containing a sufficient volume of distilled water to ensure the continued operation of the battery of cells for any desired interval, is a distributing pipe *g* having a plurality of leads *g'*, one or more adjacent each cell, the outlets of which leads pass within the cell and open thereto at a point slightly below the normal level of the electrolyte in the cell. Each of the branch leads are valve controlled, any desired type of valve as *h* being used.

These branch pipes are preferably formed of two sections *g''* and *g'''*, which communicate with each other through the medium of a fill cup *i* open to atmosphere, this construction having the three-fold object of permitting the use of the feed pipe in the event of a blowout to vent the cell, to ensure a constant hydrostatic pressure upon the feed water, and to facilitate the application of the actuating valve mechanism to

the feed water system and a more thorough insulation of this system so as to avoid any possible grounding of the circuit therethrough.

5 Slidably mounted upon the section g^3 is a float j so constructed as to be immune to the action of electrolyte thereon. This float is connected in any desired manner as by the brackets j' , to a connecting rod k passing vertically through the branch pipe g^3 and pivotally connected to a rocking lever m pivoted to the bracket m' , the short arm of this lever being connected with the valve h . The length of the two arms of the lever m is so proportioned that the valve will be opened only with a predetermined variance of the level of the electrolyte in a cell. The connecting rod k has an insulating section k' therein, which, together with the gap between the end of the pipe g^2 and the cup h , will effectively insulate the water feed system from the cell.

The main distributing pipe g will extend parallel to each row of cells in a battery and a branch lead similar to g' will extend therefrom so as to discharge into adjacent cells. By using a valve h in each of the several leads, the supply of water to each cell is entirely independent of the supply to any other cell, notwithstanding that all cells are supplied from a common source, and is determined solely by the working conditions within the cell fed through that valve.

35 The discharge pipe g' , g^2 and g^3 leading into each cell, opens within the body of the cell as distinguished from any of the troughs, so that the rise and fall of the float i will be responsive only to the rise and fall of the main body of electrolyte in the 40 cell which will be more nearly proportionate to the rate of decomposition of the water of the electrolyte than the rise and fall of the electrolyte in any of the troughs would be. Furthermore, this arrangement of the actuating means for the valve affords ample 45 space for this mechanism and permits the use of pipes sufficiently large to ensure the rapid delivery of distilled water to within the tank.

The operation of the herein described 50 mechanism is substantially as follows:—

In describing the operation of the device, it will be assumed that the tank a contains caustic soda, but has no distilled water therein. Under this condition, the float j will be in its lowermost position, and by its weight, and the weight of the rod $k-k'$, will have oscillated the arm m and fully opened the valve h . Under this condition, distilled water will run from the tank a 55 through the pipe g , branch pipe g' and section g^2 thereof, into the fill cup i and thence through the branch g^3 of the lead g' into the tank until the solution in the tank reaches a level which will raise said float j , thus 60 rocking the arm m in the opposite direction

to close the valve h through the medium of the connecting rod $k-k'$.

Since the section g of the lead g' is open to atmosphere through the fill cup i , and since the seal about the top of the tank will not be closed until the level of the electrolyte in the cell approaches the normal working level, it is apparent air will not be compressed in the cell in a manner to interfere with the free flow of distilled water thereinto. 70

With the flow of the electric current through the cell, and the resultant decomposition of the water of the electrolyte, there will be a drop of the level of the electrolyte within the cell due in part to the evolution of the gases and in part to the development of slight pressure in the gas chambers at the top of the cell. At the same time there will be a rise in the level of the electrolyte in the trough between the walls a' and a'' . The electrolyte will also rise in the branch g^3 of the lead g' and the fill cup i , since it is apparent that as the lower end of this branch g^3 becomes submerged in the liquid within the cell, it will be necessary to build up the supply of water in said branch g^3 and the cup i in order to secure sufficient head to cause the water to flow so as to bring the electrolyte in the cell to the desired level. 80

With a continued drop of the level of the electrolyte in the cell, distilled water will flow from within the cup i through the branch g^3 into the cell, thus instantly restoring the normal level of the electrolyte until conditions within the cell and at the fill cup are such that before water will flow from the cup i to within the cell, the drop in the level of the electrolyte will be sufficient to permit the fall of the float j in a manner to open the valve h . This opening of the valve will deliver distilled water to the cup i until a sufficient head of water has been built up to cause it to flow readily to within the tank until the normal level of the electrolyte therein has been restored. 90

Under no circumstances will the distilled water ever flow in any substantial volume, there being an intermittent rise and fall of the float as working conditions within the cell demand, thus ensuring the presence of sufficient water in the cup i and branch g^3 of the lead g' to effectively seal the feed water system in a manner to prevent the escape of gases therethrough, except in the event of the development of excessive pressures within a cell due to a failure, for some reason, to evacuate gases generated with sufficient rapidity. 100

By thus automatically and constantly renewing the supply of distilled water, the dangers of a blowout are very greatly reduced, since there is no likelihood of the electrolyte reaching a subnormal level through a failure of the feed water system. 115

4

By mounting the float *j* upon the branch pipe *g*, I ensure the opening of the valve *h* before the discharge end of said pipe is opened to the space within the gas chamber *b* above the surface of the electrolyte, and thus guard against any possibility of the escape of the gases through this pipe before the valve *h* has been opened to ensure the delivery of a fresh supply of distilled water.

10 I prefer to use an interrupted lead with a fill pipe arranged in the length thereof, since this affords an additional factor of safety and at the same time avoids the necessity for the use of a stuffing box about 15 the connecting rod *k*—*k'* with resultant possibility of such friction as might cause a failure of the mechanism to act with the light power afforded by the float and its 20 appurtenances. This construction could be used, however, but would not be found as efficient in use as that herein described.

By locating the float within the tank *a* instead of the outer trough between the walls *a'*—*b'*, or the inner troughs formed 25 by the walls *b'*—*a*², *b*²—*a*² and *b*²—*b*³, I am enabled to secure a feed of the water more 30 nearly in accord with the rate of decomposition of the water of the electrolyte, since changes of pressure conditions will cause greater variance in the level of the electrolyte in said troughs than in the greater body 35 of electrolyte in the body of the tank *a*. The level of the liquid in the trough open to atmosphere is subject to a material rise 40 and fall with slight pressure variation within the cell and with but a small displacement of electrolyte. Consequently with a rise of the level in this trough, the valve *h* would be closed notwithstanding that such 45 a use would occur only with a lowering of the level of the electrolyte in the cell. Furthermore with a drop of gas pressure within the cell, the level of the water in the trough would become lower, although the level of electrolyte in the cell would become 50 higher so that the valve *h* would be opened with a rise of level in the cell.

While I have shown the section *g* of the lead *g'* as opening within the cell adjacent to the anode, this is largely a matter of convenience, as there is greater clearance at this point.

It is not my intention to limit the invention to the precise details of construction shown in the drawings, it being apparent that such may be varied without departing from the spirit and scope of the invention.

Having described the invention, what I claim as new and desire to have protected by Letters Patent, is:—

1. An electrolytic cell embodying therein a casing, means dividing the lower part of said casing into a plurality of communicating electrolyte compartments and the upper part thereof into a plurality of non-

communicating gas chambers, means communicating with the cell below the normal level of the electrolyte therein and with atmosphere, whereby said electrolyte may flow between said cell and said means with varying pressure conditions therein, a pipe leading from a source of distilled water supply and discharging within a cell below the normal level of the electrolyte therein, a valve arranged in said pipe, and actuating means for said valve comprising means responsive to variations of the level of the electrolyte in the cell, and operative connections between said means and said valve whereby said valve will be opened when the electrolyte in the cell reaches a subnormal level and will be closed when the electrolyte in the cell is at the normal level.

2. An electrolytic cell embodying therein a casing, means dividing the lower part of said casing into a plurality of communicating electrolyte compartments and the upper part thereof into a plurality of non-communicating gas chambers, means communicating with the cell below the normal level of the electrolyte therein and with atmosphere, whereby said electrolyte may flow between said cell and said means with varying pressure conditions therein, a pipe leading from a source of distilled water supply and discharging within a cell below the normal level of the electrolyte therein, a valve arranged in said pipe, and actuating means for said valve comprising a float slidably mounted upon said pipe within the cell, whereby it will rise and fall with variations of the level of the electrolyte therein, and operative connections between said means and said valve whereby said valve will be opened when the electrolyte in the cell reaches a subnormal level and will be closed when the electrolyte in the cell is at the normal level.

3. An electrolytic cell embodying therein a pipe leading from a source of distilled water supply and discharging within a cell below the normal level of the electrolyte therein, a valve arranged in said pipe, and actuating means for said valve comprising a float slidably mounted upon said pipe within the cell, whereby it will rise and fall with variations of the level of the electrolyte therein, a rod passing through said pipe, connections between the lower end thereof and said float, and a rocking lever having one arm thereof operatively connected with said valve and the other arm thereof pivotally connected with said rod, whereby said valve will be opened when the electrolyte in the cell reaches the subnormal level, and will be closed when the electrolyte in the cell is at the normal level, said rod being insulated in relation to said valve.

4. An electrolytic cell embodying therein

a pipe leading from a source of distilled water supply and discharging within a cell below the normal level of the electrolyte therein, said pipe being formed in two sections, the adjacent ends of which are spaced apart, a container for distilled water about the adjacent ends of said pipe sections, a valve arranged in said pipe, and actuating means for said valve comprising means responsive to variations of the level of the electrolyte in the cell, and operative connections between said means and said valve whereby said valve will be opened when the electrolyte in the cell reaches a subnormal level and will be closed when the electrolyte in the cell is at the normal level.

5. An electrolytic cell embodying therein a pipe leading from a source of distilled water supply and discharging within a cell below the normal level of the electrolyte therein, said pipe being formed in two sections, the adjacent ends of which are spaced apart, a container for distilled water about the adjacent ends of said pipe sections, a valve arranged in said pipe, and actuating means for said valve comprising a float slidably mounted upon said pipe within the cell, whereby it will rise and fall with variations of the level of the electrolyte therein, and operative connections between said means and said valve whereby said valve will be opened when the electrolyte in the cell reaches a subnormal level and will be closed when the electrolyte in the cell is at the normal level.

6. An electrolytic cell embodying therein a pipe leading from a source of distilled water supply and discharging within a cell below the normal level of the electrolyte therein, said pipe being formed in two sections, the adjacent ends of which are spaced apart, a container for distilled water about the adjacent ends of said pipe sections, a valve arranged in said pipe, and actuating means for said valve comprising a float slidably mounted upon said pipe within the cell, whereby it will rise and fall with variations of the level of the electrolyte therein, a rod passing through said pipe, connections between the lower end thereof and said float, and a rocking lever having one arm thereof operatively connected with said valve and the other arm thereof pivotally connected with said rod, whereby said valve will be opened when the electrolyte in the cell reaches the subnormal level, and will be closed when the electrolyte in the cell is at the normal level, said rod being insulated in relation to said valve.

7. An electrolytic cell embodying therein a tank forming the outer electrode, a cover therefor, means adjacent the edge of said tank and said cover dividing the upper part of said tank into two non-communicating

gas chambers, and forming a liquid seal 65 about the upper edge thereof communicating with atmosphere, a fill cup carried by said cover, a pipe section leading from adjacent the bottom thereof to within said tank and terminating below the normal level of the 70 electrolyte therein, a tank containing a supply of distilled water, a second pipe section leading therefrom and discharging into said fill cup, said two pipe sections forming means for delivering distilled water from 75 said supply tank to said first named tank, having a gap in the length thereof surrounded by said fill cup, whereby gases from the gas chamber through which said first named pipe section passes may escape to 80 atmosphere in the event of a blowout, a valve arranged in said pipe section opening into said fill cup, and actuating means for said valve comprising a float slidably mounted upon said pipe within the cell, whereby it will rise and fall with variations of the 85 level of the electrolyte therein, a rod passing through said pipe, connections between the lower end thereof and said float, and a rocking lever having one arm thereof operatively 90 connected with said valve and the other arm thereof pivotally connected with said rod, whereby said valve will be opened when the electrolyte in the cell reaches a subnormal level, and will be closed when the 95 electrolyte in the cell is at the normal level, said rod being insulated in relation to said valve.

8. The combination with a plurality of electrolytic cells, a tank containing a supply 100 of distilled water, and a pipe leading therefrom and extending adjacent each of said cells, of a plurality of leads therefrom adjacent and discharging within said cells respectively below the normal of the electrolyte therein, each of said leads having a valve arranged therein, and actuating means 105 for said valves respectively comprising means responsive to variations of the level of the electrolyte adjacent the discharge end 110 of the lead containing the valve, and operative connections between said means and said valve, whereby the valve associated with each cell will be opened when the electrolyte in that cell reaches the subnormal level, and will be closed when the electrolyte is at the 115 normal level, and the delivery of distilled water to each of said cells will be independent of every other cell and will be controlled by the conditions within that cell alone. 120

In witness whereof I have hereunto affixed my signature, this 26th day of May, 1920, in the presence of two subscribing witnesses.

ISAAC H. LEVIN.
